UNITED STATES PATENT OFFICE.

EDMOND D. MOREAU, JR., OF MOOSUP, CONNECTICUT.

MIRROR-SUPPORT.

1,145,259.

Specification of Letters Patent.

Patented July 6, 1915.

Application filed October 9, 1914. Serial No. 365,867.

To all whom it may concern:

Be it known that I, EDMOND D. MOREAU, Jr., a citizen of the United States, residing at Moosup, in the county of Windham and State of Connecticut, have invented new and useful Improvements in Mirror-Supports, of which the following is a specification.

This invention relates to improvements in 10 mirror supports, and has particular application to a device for holding a mirror on the carriage of a cotton drawing machine, whereby the cotton passing through the reeds of the machine will be reflected so that 15 the operator of the machine may at all times view the cotton passing through the reeds without leaving his seat.

In carrying out the present invention, it 20 is my purpose to improve and simplify the general construction of mirror supports and to provide a support which will hold the mirror in such manner as to enable the latter to be thrown at any desired angle and held at such angle.

25 With the above and other objects in view, the invention consists in the construction, combination and arrangement of parts hereinafter set forth in and falling within the scope of the claims.

30 In the accompanying drawings:—Figure 1 is a view in front elevation of a mirror support constructed in accordance with the present invention; Fig. 2 is a sectional view on the line 2—2 of Fig. 1; Fig. 3 is a sectional view on the line 3—3 of Fig. 1.

Referring now to the drawing in detail, 1 35 designates a vertical standard or post having the lower end thereof threaded, as at 2, to engage the opening 3 formed in the bed 40 plate 4 of the carriage of a cotton drawing machine. The upper end of the standard 1 is bent at right angles to itself, as at 5 and lies in a substantially horizontal plane. Surrounding the horizontal limb 5 and capable

45 of sliding and rotary movements on such limb is a collar 6 equipped with a set screw 7 adapted to engage the limb 5 so that a rigid connection may be established between said limb and the collar to hold the collar 50 against movement on the limb. The outer surface of the collar 6 at a point diametrically opposite the set screw 7 is flattened as at 8, and placed in face to face contact with the flattened portion 8 of the collar is the 55 interconnecting portion of a substantially U-shaped yoke 9, such interconnecting por-

tion being formed with an opening 10 aligning with an aperture 11 formed in the flat surface of the collar to receive a securing screw 12, whereby the yoke is rigidly fastened to the collar. The limbs of the yoke 9 are preferably yieldable and formed integral with the outer extremities thereof and projecting in opposite directions are fingers 12', 12' having the outer extremities thereof 60 bent upon themselves to provide jaws 13.

14 designates a mirror adapted to be placed within the jaws 13 carried by the fingers 12' and having the end edges thereof formed with depressions 15 to receive the 70 jaws 13. Connecting the limbs of the yoke 9 adjacent to the fingers 12' is a coiled contractile spring 16 acting to draw the jaws toward each other so that the mirror will be effectively gripped and held to the fingers. 75

In practice the standard 1 is threaded into the opening 2 in the bed plate 4 of the carriage of the cotton drawing machine and the mirror 14 placed within the jaws 13, the jaws being moved away from each other 80 against the action of the spring 16 to receive the mirror and subsequently release the same, so that the spring will react and hold the mirror to the fingers. The collar 6 is now adjusted along the limb 5 to the desired position, and the set screw 7 tightened to hold the mirror against accidental displacement. 85

When the mirror has been properly adjusted, the operator sitting at the front of the machine may at all times see the reeds 90 and the cotton passing through the reeds, thereby eliminating the necessity of leaving his seat and walking around to the rear of the machine.

I claim:—

1. A mirror support of the class described comprising a vertical standard having the upper end thereof bent at right angles to itself to provide a horizontal limb, a collar mounted upon said limb and capable of 100 longitudinal and rotary movements on said limb, means for holding said collar in adjusted position on the limb, a yoke secured to said collar, fingers carried by said yoke and extending outwardly therefrom in opposite directions, jaws on the outer end of said fingers, a mirror within said jaws and a spring carried by said yoke and acting upon the latter to draw the jaws toward each other to grip the mirror. 105

2. A mirror support of the class described comprising a vertical standard having the

lower end thereof screw-threaded to engage an opening in the bed plate to engage an opening in the carriage of the cotton drawing machine and the opposite end thereof bent at right angles to itself to form a horizontal limb, a collar mounted upon said limb and capable of longitudinal and rotary movements on said limb, a set screw mounted upon said collar to hold the latter in adjusted position on the limb, a U-shaped yoke having resilient limbs, a rigid connection between the interconnecting member of said yoke and said collar, fingers formed on the

outer end of the limbs of said yoke and projecting in relatively opposite directions, jaws 15 on the outer extremities of said fingers, a mirror within said jaws and a spring connecting the limbs of said yoke and acting upon such limbs to draw the jaws toward each other.

In testimony whereof I affix my signature in presence of two witnesses.

EDMOND D. MOREAU, JR.
